DESIGN FOR AN INDUSTRIAL SPRAY GUN

Carl G. Neidhardt, Chattanooga, Tenn., assignor
to Taywal Corporation, Chattanooga, Tenn., a
corporation of Tennessee

Application September 12, 1936, Serial No. 64,831

Term of patent 7 years

To whom it may concern:

Be it known that I, Carl G. Neidhardt, a citizen of the United States, residing at Chattanooga, in the county of Hamilton and State of Tennessee, have invented a new, original, and ornamental Design for an Industrial Spray Gun, of which the following is a specification, reference being had to the accompanying drawing, forming a part thereof.

In the drawing, Fig. 1 is a side view of the industrial spray gun showing my new design, and Fig. 2 is a front elevation of said industrial spray gun.

I claim:

The ornamental design for an industrial spray gun, substantially as shown.

CARL G. NEIDHARDT.
